UNITED STATES PATENT OFFICE

MILTON ALDEN, OF BROCKTON, MASSACHUSETTS, ASSIGNOR TO RADIO INVENTIONS, INC., A CORPORATION OF NEW YORK

ELECTRICAL CONNECTOR

Original application filed January 26, 1928, Serial No. 249,685. Divided and this application filed December 4, 1930. Serial No. 499,957.

My invention relates to radio receiving apparatus and particularly to what is sometimes termed adapters or converters.

One object is to provide a device of this character which is compact and reliable and capable of embodiment in various forms and arrangements.

Another object is to provide a construction for use with vacuum tubes having prongs which will facilitate the insertion of the prongs into the device.

Another object is to facilitate identification of the device and to indicate the type of tube which it is designed to receive.

15 Another object is to provide a device for the adaption of a five pronged tube to a four prong socket.

Another object is to provide an adapter or socket construction capable of receiving a 20 resistance which may be conveniently inserted in one or more lines without the use of tools or binding posts.

Another object is to provide a construction which will facilitate the introduction of 25 means for readily varying or controlling the regeneration in the radio frequency circuit of a receiver.

Another object is to provide means for the conversion of a radio receiver designed to 30 operate with vacuum tubes whose cathodes are heated by direct current to a type adapted to employ tubes whose cathodes are operated either directly or indirectly from an alternating current source.

35 Another object is to provide a construction, the parts of which are capable of being assembled in various different relations.

In the form shown the device consists of 40 two parts, a base and a top, both formed of insulating material and secured together in a suitable manner, as for instance by a central stud or rivet.

The base part carries a number of projecting prongs adapted to be inserted in a socket 45 of any usual type. Spring contacts may be secured to the inner ends of a number of these prongs depending on the purpose to which the device is to be put.

50 The top part is provided with a number of passages arranged in line with the various

contacts and adapted to receive the prongs of a tube to be connected in the circuit.

The top and base are also constructed to accommodate one or more connectors consisting of an interior contact and an external circuit terminal for the connection of external elements into the system. One of the contact devices within the base consists of two parts adapted to be separated and permit the insertion of an additional modifying or connecting element within the device.

The top member is preferably provided with a directing and identifying groove which intersects the entrance ends of all the passages.

Fig. 1 is a vertical sectional view of one form of device embodying my invention and showing a removable resistor in connection with one of the contacts.

Fig. 2 is a plan view of the base member but omitting some of the contacts.

Fig. 3 shows the inside of the top member.

Fig. 4 is a perspective view of a resistor adapted to be inserted in the device, the scale being somewhat larger than that of Fig. 1.

Fig. 5 is an exploded perspective view of the parts of the resistor.

Fig. 6 is a fragmentary sectional view of the device of Fig. 1 but omitting the resistor.

Fig. 7 is a perspective view of one of the removable contact members.

Fig. 8 is a detail view of another form of contact.

The base 10 and the top 11 are preferably formed of insulating material moulded to the desired shape and having flanges 12 and 13 respectively, which overlap each other but are spaced apart somewhat. These two members may be conveniently secured together by a tubular rivet 14.

The base carries a number of prongs of the usual type such as 15, 16, 17 and 18 which project from the lower side.

Contact members such as 19 and 20 are secured to the upper ends of some of the prongs, for instance to the prongs 15 and 16. The upper ends of other prongs may be insulated or cut off by a layer of insulating material such as 21.

A connector 22 has a spring contact finger 23 at one end connected to it by a U shaped portion 24 which is adapted to fit around the lower edge of the flange 13 inside of the flange 12. These overlapping flanges grip the connector and hold it in place. The connector has an external terminal 25 of suitable type for convenience in the attachment of a conductor.

The top member is preferably provided with projecting shoulders such as 26 and 26' between which one arm of the U shaped member 24 is positioned when the parts are assembled. This top member is also preferably provided with a conical wall 27 which serves as an abutment for the contact tips 20 and 23 and the like.

The contact member 29 has a lug 30 at its base adapted to be located in a recess 31 where it is held by pressure between the top and base members when they are secured together. This member 29 also has a spring tip 32 which, when the parts are in the position shown in Fig. 6, engages the contact finger 19.

The top member 11 is provided with a number of passages such as 33, 34, 35 and 36 adapted to receive the prongs of the tube to be used in the device.

The top member is preferably provided with a groove 37 which provides inner and outer annular shoulders for accurately guiding the prongs of a tube to be inserted. This greatly facilitates the insertion of the tube in the proper position. This element is of considerable importance in modern radio set construction because of the compact arrangement of the parts of the apparatus which makes it difficult not only to see where the prong openings are but even very difficult to find the openings.

The walls of these grooves are preferably colored according to some prearranged code, for instance green for a five prong tube, orange for a power tube and red for other tubes. In fact these rings may be painted with phosphorescent or other luminous paint so as to facilitate finding the entrance to the sockets even in the dark.

The top member is also provided with a slot or passage 38 in line with the tips of the contact members 19 and 32 to facilitate the insertion of any member desired to be connected with either or both of these contacts.

The resistor may be constructed as shown in Figs. 4 and 5. 40 is a piece of insulating material on which is wound the resistance wire 41 having terminals 42 and 43. On either side of the form 40 is placed an insulating piece 44 and against these pieces are placed the metal parts 45, each having a single lug 46 on one extremity and a pair of lugs 47 on the other extremity. These lugs are bent over as shown in Fig. 4 to hold the parts together and the lugs 46 engage the

bare ends 42 and 43 of the resistance wire and contact therewith so that each metal plate forms a terminal for the resistor.

A resistor is adapted to be inserted between the contacts 19 and 32 so as to insert a resistance in the circuit to which the prong 15 is connected, as for instance in the grid circuit.

If a resistor is not desired it may be removed, in which case the contacts 19 and 32 automatically engage each other and thus close the circuit.

It should be understood that a connector such as 22 with the attached contact finger 23 may be used in any of the electrode circuits and that when it is used the corresponding prong of the adapter may be insulated or blanked from the circuit by insulation such as 21. It should also be understood that an external connector might be inserted between the contacts 19 and 32 if it is desired to tap the circuit at this point.

The inclined spring contacts such as 20 and 23 are designed preferably so as to normally bear on the tapered or inclined part 27 of the top member. These contacts bend not only at their tips but along their whole lengths. When the tube prongs are inserted these contacts are bent outwardly so as to afford a maximum perfection of contact.

It will be obvious that the prongs may be inserted into the ordinary type of push socket but I have also provided a pin 50 so that it may be used in the ordinary type of bayonet slot socket.

It will be seen that the construction thus far shown and described is capable of use in many different ways, for instance such a construction permits the connection of an external source of current such as a microphone or a phonograph pickup to the input of the detector tube of an ordinary receiver and the use of such tube as an amplifier.

It is also possible to isolate any tube electrode desired from the corresponding connection in the socket and allow an independent exterior connection to be made by one of the connectors such as 22.

It is also possible by such a device to insert a resistor such as shown in Fig. 4 and thus adequately control the cathode heating current of a tube in an already manufactured set where such set was not provided with such adequate control. Additional resistance can be readily inserted into the set without the employment of tools or external apparatus. By such a construction a controlling resistance may be inserted into any circuit of a tube.

The mechanical construction of the device is such that the various parts can be made according to standard specifications and assembled in various combinations and arrangements depending upon the use to which the device is to be put.

This application is a division from my application No. 249,685, filed January 26, 1928, in which parent application I have claimed the construction which involves the 5 connector strip 22 clamped between the overlapping flanges such as 12 and 13 and having an interior spring contact such as 23 and an external connection such as 22 and features related to such construction and combination.

I claim:

1. An electrical connector comprising a base having projecting terminal prongs, a top member secured to said base and having 15 passages for the reception of tube prongs, a contact member connected to one of the base prongs, a second contact member mounted adjacent thereto alongside of one of the passages in said top member and normally engaging the other contact member, said top having an aperture for the insertion and removal of a device through the top between the contact members.

2. An electrical connector comprising insulating supporting means, a number of contacts mounted therein and having external circuit terminals, said insulating means being provided with passages to permit the insertion of the prongs of a tube, one of said 30 contacts consisting of two parts adapted to resiliently engage one another, one of said parts being adjacent one of the passages to permit engagement by the prong of a tube, the other part being electrically connected to 35 one of the external circuit terminals, said insulating means having an aperture to permit the insertion of a device between the two said parts.

3. An electrical connector comprising a 40 base member having external circuit terminals and internal contacts, a top member having passages to permit the introduction of tube prongs and having an internal chamber housing said contacts, said top member having inclined walls intersected by said passages, at least some of said contacts having inclined resilient tips biased toward said inclined walls and means for securing the top and base members together.

50 4. An electrical connector comprising an insulating base having an external circuit terminal, a top member secured to said base and having a peripheral flange, a contact secured to said external circuit terminal and 55 having a portion located adjacent said flange, a resilient contact located alongside of and normally engaging said first mentioned contact, said top having a passage alongside of said resilient contact for the insertion of a tube prong and an aperture spaced apart from said passage to permit the insertion of a device between said contacts.

5. A tube connector comprising insulating base and top members, said base having projecting prongs and said top member having

passages for tube terminal pins, contact members mounted between said members in line with said passages, and a contact connected to at least one of said prongs adjacent and normally biased toward one of said contact members, said top having a passage for the insertion of a resistance between the adjacent contact members. 70

6. An electrical connector comprising an insulating base having external electrical terminals, an insulating top having an internal boss and a peripheral flange with a chamber between the boss and flange and having a number of passages for the prongs of a vacuum tube, inverted V-shaped spring members mounted in said chamber, each spring member having an outer arm supported adjacent the base and an inner contact arm extending inclined across the inner end of one of the passages on the top to receive the prong of an inserted tube and means for securing the boss of the top to the base with the flange of the top surrounding the spring members adjacent the base. 75 80 85

7. An adapter for vacuum tubes comprising two insulating members, one constituting a base and the other a top, one of which members has a flange with a chamber facing the other member, the top member having a prong passage, a pin terminal projecting from the base member, a spring contact in said chamber and having a foot connected to said pin terminal and having a resilient contact finger in line to be engaged by a prong inserted in said passage. 90 95 100

8. A connector for vacuum tubes comprising two insulating members, one of which has two passages through its top, two contact members secured to the other member with contact faces arranged in line to be engaged by devices inserted through the respective passages, at least one of said contact members being resilient and engaging the other contact member and means for securing said members together. 105 110

9. An electrical connector comprising two insulating members, one of which has passages for reception of tube prongs, a contact member having an arm clamped between said members and held solely thereby and having a resilient contact portion disposed adjacent one of the passages to be engaged by a prong when inserted in the adjacent passage, said arm having an angular anchorage tip spaced laterally away from the contact portion, one of said members having a recess in which said tip is anchored and means independent of the contact members for holding the two insulating members together and clamping said arm between them. 115 120 125

10. A vacuum tube socket comprising upper and lower insulating members, the upper member having at least three passages for tube prongs, a conductor member having an arm held in position solely by said insulat- 130

ing members and having a resilient spring contact extending in line to be engaged by a tube prong inserted through one of said passages, said lower member having a recess adjacent said passage and said conductor member having a positioning lug at its inner end bent at right angles to the arm and fitted in said recess and means for securing said upper and lower insulating members together 10 and holding said arm in place with its lug in said recess.

11. An electrical connector for vacuum tubes having prongs comprising an insulating body formed of two parts, namely an upper part and a lower part, the upper part having a number of apertures to receive the inserted prongs of a tube, a conductor for each aperture, one conductor having an anchorage portion at its inner end and an external circuit terminal at its outer end with a laterally resilient contact portion between the inner and outer ends arranged alongside at least one edge of the adjacent aperture to be engaged by the inserted tube prong, the 25 inner end of said conductor having a portion held between adjacent surfaces of the two parts of the body and a hook-like tip, one part of the body having a recess into which said hook-like tip projects whereby the 30 inner end of the conductor is held from movement.
